UNITED STATES PATENT OFFICE.

EIGIL AAGE HANSEN, OF COPENHAGEN, DENMARK.

CENTRIFUGAL PUMP.

1,143,957.

Specification of Letters Patent. Patented June 23, 1915.

Application filed June 12, 1913. Serial No. 773,159.

To all whom it may concern:

Be it known that I, EIGIL AAGE HANSEN, subject of the King of Denmark, residing at Nordre Fasanvej 32, Copenhagen, Denmark, have invented certain new and useful Improvements in or Relating to Centrifugal Pumps, of which the following is a specification.

The present invention relates to centrifugal pumps and has for its object to provide an improved pump which may be used for the most varying purposes, but will be herein described particularly with reference to its employment as a milk pump. It is particularly suitable for this purpose inasmuch as it conveys the milk to the desired place without the occurrence of any frothing. In order entirely to prevent frothing means must be provided for permitting the excess of air present in the liquid to leave the pump by an opening other than that by which the liquid is expelled so that the latter is not mixed with the air, when it leaves the pump. This end is attained according to this invention by causing the air to leave the pump at the pressure end. For this purpose a small space for the egress of the air may be provided between the shaft and the hole in the back cover, through which the shaft passes and which is at the pressure end of the pump body. If the pump is provided at this end with a stuffing box, the desired end may be attained by boring out the shaft in the direction of its length and providing transverse holes communicating with the interior of the pump and with the hollow interior of the shaft, so that the interior of the pump is thereby put into communication with the atmosphere.

When the liquid enters the body of the pump it is thrown with great force against the interior peripheral wall of the pump, the froth bubbles containing air burst and the air is then forced out into the atmosphere as hereinbefore mentioned. The liquid thus rendered free of air is then incapable of forming froth.

In order to avoid loss of liquid through the air path, the pump should be set in motion before the liquid is introduced. When the work is finished and the pump is to be put out of operation the liquid present in the pipe should be drawn off by a special tap provided beneath it.

In the pumping both of milk and of other liquids there sometimes occur, however, other disturbances in connection with which the present invention is of importance—as for instance, when the flow into the pump, for example through its feed pipe is irregular. Provided that no more liquid runs down into the feed pipe than can flow quickly into the pump, there will be no disadvantageous occurrences since in this case any air, which may be present with the liquid finds a free return path again into the feed pipe. When however the inflow is so rapid that the feed pipe is filled, the air cannot get back into the atmosphere and the pump ceases to work satisfactorily. The liquid in the feed pipe flows back, after which the pump again takes up some of it, the liquid runs back again, and so on. These disturbances, which occur with all centrifugal pumps, are entirely eliminated by the arrangement herein described.

The invention is illustrated in the accompanying drawing showing a sectional view of an apparatus embodying the invention.

The driving shaft *f* carries belt pulleys *g* and runs in bearings *h* in the frame work of the pump. The end of the shaft shown in the drawing on the left-hand side projects into the body of the pump and carries the impeller which is fastened thereto at its broad end and runs in a conical two-part casing formed by the conical fore part *a* and the back cover *b*. The conical fore part *a* is closed at the wider or pressure end by the back cover *b*, through which passes the shaft *f*.

It will be noted that the shaft is bored out longitudinally at *i* and transverse holes *e* are provided which communicate therewith and with the interior of the pump body.

I claim:—

1. A centrifugal pump comprising a pump body, a shaft carrying an impeller adapted to rotate in the said body and means arranged at the pressure end of the pump whereby the interior of the said body is in the pump with the outer atmosphere.

2. A centrifugal pump comprising a pump body, a longitudinally bored shaft, and an impeller carried by said shaft and adapted to rotate in the said body, said shaft connecting the interior of the pressure end of the pump with the outer atmosphere.

3. A centrifugal pump comprising a pump body, a longitudinally bored shaft, an impeller carried by said shaft and adapted to rotate in the said body, said shaft having a plurality of holes connecting the interior of the pressure end of the pump with the bore of the shaft.

In testimony whereof I have affixed my signature in presence of two witnesses.

EIGIL AAGE HANSEN.
